UNITED STATES PATENT OFFICE.

THOMAS A. SEARLE, OF QUIDNICK, ASSIGNOR TO ROBERT BARTON, OF PROVIDENCE, RHODE ISLAND.

DESIGN FOR A SLEEVE-BUTTON BACK.

SPECIFICATION forming part of Design No. 14,106, dated July 17, 1883.

Application filed April 30, 1883. Term of patent 7 years.

To all whom it may concern:

Be it known that I, THOMAS A. SEARLE, of Quidnick, in county of Kent and State of Rhode Island, have invented a new and original Design for Sleeve-Button Backs; and I do hereby declare the following specification, taken in connection with the accompanying drawings, forming a part of the same, to be a description thereof.

This design relates to the shoe or back of a sleeve-button; and it consists in a back having a rectangular outline with rounded corners, and preferably convex on its outer surface in the line of both its axes, although said surface may be flat, if desired.

Referring to the drawings, Figure 1 shows a rear view of a button having a back of my design, which back is of greater length than width. Figs. 2 and 3 show side views of such button at right angles to each other.

As shown in Fig. 1, the outline of the back A is a rectangle, with rounded corners *a*, and, as shown in Figs. 2 and 3, the outer surface of said back is convex, both longitudinally and transversely.

If desired, the outline of the back may be that of a square with rounded corners.

A back of the shape described is particularly adapted to that variety of buttons in which the back is pivoted to the post so as to turn down on one or both sides, and it possesses the advantages of not only being very easily inserted into the button-holes, but also of furnishing a much broader and better bearing on the cuff, thereby serving to retain the button therein more securely than a round or oval shoe.

What I claim, and desire to secure by Letters Patent, is—

1. The design herein described, consisting of a button-back having the outline of a rectangle with rounded corners, substantially as described and shown.

2. The design herein described, consisting of a button-back having the outline of a rectangle with rounded corners, and having its outer surface convex, both longitudinally and transversely, substantially as described and shown.

THOMAS A. SEARLE.
